UNITED STATES PATENT OFFICE

FRANK J. JARVIS, OF PALMER, MASSACHUSETTS, ASSIGNOR TO JARVIS AND JARVIS, INC., OF PALMER, MASSACHUSETTS, A CORPORATION OF MASSACHUSETTS

EXPANDING CLAMPING MEANS

Application filed July 11, 1930. Serial No. 467,371.

This invention relates to improvements in expanding holding or clamping means and has particular reference to such expanding means for securing a caster stem or analogous device to the article to which it is attached, and has common subject matter with my copending application filed July 11, 1930, Serial No. 467,372.

The principal object of the invention is to provide improved expanding means adapted to fit various sizes and shapes of attaching sockets or fixtures.

Another object of the invention is to provide simple and inexpensive connecting or clamping means easily adjusted to different sizes and shapes of attaching sockets or fixtures.

Another object of the invention is to provide simple, inexpensive and positively operable clamping means adapted to permit a caster stem or like object to be fitted to attaching sockets or fixtures of different sizes and characteristics.

Another object of the invention is to provide improved means for attaching and detaching the clamping means.

Another object of the invention is to provide an improved caster that may be easily and quickly attached or detached from attaching means of different sizes and characteristics provided on the articles to which the caster is to be attached.

Other objects and advantages of the invention will become apparent from the following description taken in connection with the accompanying drawings. It is apparent that many changes in the details of construction and arrangement of parts may be made without departing from the spirit of the invention expressed in the following claims. The preferred forms only have been described and illustrated by way of explanation; hence I do not wish to be limited to the exact details shown and described.

It is well known that the attaching sockets and fixtures for casters and similar devices vary in size and shape and in other characteristics. It is, therefore, one of the main objects of this invention to provide expandable means easily and positively oper-

able to accommodate these conditions. It has been found from experience in hospitals and institutions that demented and eccentric patients often detach casters and hurl them through windows or otherwise use them as weapons of attack. It is, therefore, another object of the invention to provide securing means of a nature not obviously and easily detached without special appliances adapted to the purpose. Another prime object is to provide such expandable means that are simple in construction and operation and inexpensive of production. It will readily be seen that the adaptability to various sizes and shapes of attaching means is a prime consideration in the manufacture and distribution of such devices both from the standpoint of economy and convenience.

Referring to the drawings in which similar reference characters refer to similar parts throughout:

Fig. I is a perspective view of a caster embodying the invention with some of the parts separated and removed;

Fig. II is a longitudinal cross section showing the caster stem inserted in the attaching socket;

Fig. III is a cross section on line III—III of Fig. II;

Fig. IV is a cross section on line IV—IV of Fig. II looking in the direction of the arrow; and

Fig. V is a partial view in cross-section showing a different form of lock nut beneath the bearing.

The numeral 1 indicates the socket or attaching connection which is secured to the article to which the caster or similar device is to be attached; as shown this is a tube and may be round in cross-section or of other shape.

The caster wheel 2 is rotatably mounted on the axle pin 3 in the usual manner in the caster bracket or fork 4 which is secured at 5 to the shell 6 of the bearing 7, the parts being preferably compressed together. The bearing 7 comprises an upper bearing block 8 and a lower bearing block 9 each having a bearing race or groove for the balls 10 and an inner bearing block 11 having a corre-

sponding ball race or groove for the balls 10. The parts of the bearing are held in related position by the shell 6 which is compressed over them.

6. Passing through a bushing 12 in the inner bearing block 11 is the caster stem 13 having the shouldered head 14 and a threaded upper portion 15. The shoulder of the head 14 bears on the under side of the inner bearing block 11 to position the stem 13 in related position to the parts of the caster. Surrounding the stem 13 and resting on the upper end of the inner bearing block 11 is the washer 16 which abuts the lower end of the attaching socket 1. Above the washer 16 and slideable on the stem 13 is the expandable spider plate 17 having a body portion 18 resting on the washer 16 and a plurality of outwardly and upwardly extending leg members 19 terminating in contacting facets 20 adapted to bear on the inner surface of the attaching tube 1. Above the spider plate 17 and also slideable on the stem 13 is a second expandable spider plate 21 having the body portion 22 and a plurality of outwardly and downwardly extending leg members 23 terminating in contacting facets 24 adapted to bear on the inner surface of the attaching tube 1. The legs of the lower spider plate 17 and of the upper spider plate 21 are alternately spaced so that the contacting facets 20 and 24 are nested within each other so that both may contact with the inner surface of the tube 1 as shown in Fig. I. Slidable on the stem 13 and lying within the interlocked spider plates 17 and 21 is the washer plate 25 acting as a spacer and compression member, as hereinafter described.

Surrounding the stem 13 and above the upper spider plate 21 is the spacer tube 26, the lower end of which rests on the section 22 of the upper spider plate 21. Above the tube 26 and resting thereon is another spider plate member 27 similar in construction to the spider plate member 17 and above this another spider plate member 28 similar in construction to the spider plate 21. A spacer and compression member 29 similar to the member 25 is contained within the spider members 27 and 28. Above the spider 28 is the threaded nut 30 to which the spider plate 28 is attached at 31 by compressing the member 28 into a groove therein or by other means. If desired the nut 30 may be separate from the plate 28 simply resting thereon. The legs and contacting facets of the spider plates 27 and 28 are alternately arranged as in the case of spider plates 17 and 21 and their operation and construction is otherwise the same.

In the shouldered head 14 of the stem 13 may be made a polygonal socket recess 34, see Fig. III, adapted to fit the polygonal-shaped wrench arm 32 or if desired a nut 33, Fig. V, may be employed instead. If the nut

is used an ordinary wrench may be utilized for its operation.

The method of operation is as follows: To insert the stem 13 and its fittings into the tube 1, turn the stem 13 with the wrench 32 until the parts are loosened on the stem. This action turns the threaded stem in the nut 30, allowing the extending legs of the spiders to contract inwardly towards the stem, the said spiders being made of resilient or springy material. Then insert the stem 13 with its fittings into the tube 1 until the washer 16 engages the lower end of the tube. Then turn the wrench in the opposite direction. This drives the stem 13 through the nut 30 shortening the distance between the nut 30 and washer 16. This action forces the resilient legs of the spider members outwardly until the engaging facets engage the inner surface of the tube 1 to such an extent that the stem 13 is held securely in the tube 1. The washers 25 and 29 act as spacer plates and compression members assisting the action and direction of movement of the spider legs under the action of turning the stem 13 in the nut 30. To withdraw the stem 13 from the tube 1 the action is the reverse. If the device is designed for use with a socket wrench the parts may not be easily removed by the fingers or an ordinary wrench, a desirable consideration where the devices are to be used in places accessible to demented persons or desperate prisoners, etc. It is apparent too that this device may be used for sockets either circular or other shape in cross-section and of different sizes. It is also apparent that the expanding features are of the very simplest construction and exceedingly economical to produce.

From the foregoing description it will be seen that I have provided simple, efficient and exceedingly economical means for carrying out all of the objects of the invention and of obtaining the advantages thereof.

Having described my invention, I claim:

1. In a device of the character described in combination with an attaching stem, an expansion plate on the stem having outwardly inclined expansion arms, a second expansion plate on the stem having outwardly inclined expansion arms, said arms of the two expansion plates being alternately spaced to nest one within the other, and operable means which will change the distance between the said expansion plates to extend or retract the said arms as the case may be.

2. In a device of the character described in combination with an attaching stem, an expansion plate on the stem having outwardly inclined expansion arms, said arms of the two expansion plates being alternately spaced to nest one within the other, a compression plate between said expansion plates contacting with

the arms thereof and operable means which will change the distance between the expansion plates to extend or retract the arms on the compression plate as the case may be.

- 5 3. In a device of the character described in combination with an attaching stem, a pair of expansion members on said stem separated by a spacer member, each of said expansion members comprising an expansion plate on the stem having outwardly inclined expansion arms and a second expansion plate having outwardly inclined expansion arms extending towards the arms of the first expansion plate, separate compression means engaging the two sets of arms, and operative means which will change the distance between the expansion plates of each pair of expansion members to extend or retract the expansion arms thereof as the case may be.
- 10 4. In a device of the character described in combination with an attaching stem, a pair of expansion members on said stem separated by a spacer member, each of said expansion members comprising an expansion plate on the stem having outwardly inclined expansion arms and a second expansion plate having outwardly inclined expansion arms extending towards the arms of the first expansion plate, said expansion arms of the two expansion plates being alternately spaced to nest within each other, and each of said expansion members having a compression plate interengaging the expansion arms of both of its expansion plates and operative means
- 15 which will change the distance between the expansion plates of both expansion members to extend or retract the expansion arms on the respective compression plates as the case may be.

- 20 5. In a device of the character described, a caster fork, a caster wheel rotatably mounted in the fork, a caster stem rotatably supported by the fork, an expansion plate on the stem having outwardly inclined extending expansion arms, a second expansion plate on the stem having outwardly inclined expansion arms extending towards the arms of the first expansion plate, separate compression means engaging the two sets of arms and operable means that will change the distance between the expansion plates to extend or retract the expansion arms as the case may be.

- 25 6. In a device of the character described, a caster fork, a caster wheel rotatably mounted in the fork, a caster stem rotatably supported by the fork, an expansion plate on the stem having outwardly inclined expansion arms, a second expansion plate on the stem having outwardly inclined expansion arms extending towards the arms of the first expansion plate, the arms of the two expansion plates being alternately arranged and nested one in the other and operable means that will change the distance between the said expansion

plates to extend or retract the expansion arms as the case may be.

7. In a device of the character described, a caster fork, a caster wheel rotatably mounted in the fork, a caster stem rotatably supported by the fork, an expansion plate on the stem having outwardly inclined expansion arms, a second expansion plate on the stem having outwardly inclined expansion arms extending towards the arms of the first expansion plate, said arms being alternately spaced to nest one within the other, a compression plate between the expansion plates contacting with the arms thereof and operable means which will change the distance between the expansion plates to extend or retract the expansion arms on the compression plate as the case may be.

8. In a device of the character described, a caster fork, a caster wheel rotatably mounted in the fork, a caster stem rotatably supported by the fork, a pair of expansion members on said stem separated by a spacer member, each of said expansion members comprising an expansion plate on the stem having outwardly inclined expansion arms and a second expansion plate having outwardly inclined expansion arms extending towards the arms of the first expansion plate, separate compression means engaging the two sets of arms and operative means which will change the distance between the expansion plates of each pair of expansion members to extend or retract the expansion arms thereof as the case may be.

9. In a device of the character described, a caster fork, a caster wheel rotatably mounted in the fork, a caster stem rotatably supported by the fork, a pair of expansion members on said stem separated by a spacer member, each of said expansion members comprising an expansion plate on the stem having outwardly inclined expansion arms and a second expansion plate having outwardly inclined expansion arms extending towards the arms of the first expansion plate, said expansion arms of the two expansion plates being alternately spaced to nest within each other and each of said expansion members having a compression plate interengaging the expansion arms of both of its expansion plates and operative means which will change the distance between the expansion plates of both expansion members to extend or retract the expansion arms on the respective compression plates as the case may be.

FRANK J. JARVIS.
